UNITED STATES PATENT OFFICE.

MARION L. BAGLEY, OF SANTA BARBARA, CALIFORNIA.

HAIR-RETAINING DEVICE.

No. 857,222.

Specification of Letters Patent.

Patented June 18, 1907.

Application filed January 8, 1907. Serial No. 350,677.

To all whom it may concern:

Be it known that I, MARION L. BAGLEY, a citizen of the United States, residing at Santa Barbara, in the county of Santa Barbara and 5 State of California, have invented certain new and useful Improvements in Hair-Retaining Devices, of which the following is a specification.

My invention relates to improvements in 10 means for securing hair-retaining devices in place and thereby preventing their loss by slipping out of the hair, a most frequent occurrence at present; and the object of my invention is to provide a device of the class 15 described which will prove cheap in manufacture, simple in construction and efficient in operation.

In the drawings illustrating the principle 20 of my invention and the best mode now known to me of applying that principle, Figure 1 shows the hair-pin; Fig. 2 represents the cap in sectional view and in engagement with the prongs of the hair-pin; Fig. 3 shows the parts assembled; Fig. 4 is a central 25 sectional view of the cap; and Fig. 5 is a sectional view on the line A—A of Fig. 3.

Both the prongs or legs *a* of the hair-pin *b* are pierced with holes *c* near the ends. The cap *d* is formed with a socket *e* into which 30 project the studs *f* from the interior wall of the cap. The opening into the socket *e* is narrow, being of about the same width as the thickness of the prongs *a*. This permits the free insertion of the prongs and serves to aid 35 in guiding them into engagement with the studs *f*.

The distance from the bottom of the socket to the studs is substantially the same as the

distance of the holes *c* from the lower end of the prongs. Hence, when the prongs are 40 forced home against the bottom of the socket, the studs and the holes will register with each other.

The operation will be readily understood from the foregoing description. After passing 45 the hair-pin through the hair, the prongs are compressed slightly to bring the points so close together as to avoid the studs *f*, when the points are inserted in the cap. This is shown by the dotted line position of the 50 points in Fig. 2. The cap *d* is passed over the points of the prongs *a* until the latter are seated in the socket *e*, when the pressure on the prongs *a* is removed. The prongs will then spring into place, the studs *f* entering 55 the holes *c*, as shown in Fig. 2. The narrow width of the opening of the socket *e* brings the holes *c* and studs *f* into register, since the prongs have practically a sliding fit and cannot wobble about in the socket. 60

What I claim is.

In a device of the character described, the combination of a hair-pin the prongs of which are resilient and are pierced each with a hole near its free end; and a cap formed with a 65 socket from the interior wall of which project toward each other studs adapted to engage in the holes in said prongs; the distance of said holes from the lower end of said prongs being substantially the same as the distance of 70 said studs from the bottom of said socket.

MARION L. BAGLEY.
